(57) **CLAIM**

The ornamental design for a storage box, as shown and described.

DESCRIPTION

FIG. 1 is a front, top and right side perspective view of a storage box in a closed position;

FIG. 2 is a top plan view thereof;

FIG. 3 is a bottom plan view thereof;

FIG. 4 is a rear, bottom, and left side perspective view;

FIG. 5 is a front, top and right side perspective view of the storage box of FIG. 1 in an open position; and,

FIG. 6 is a top plan view thereof.

The broken lines in FIGS. 3 and 6 illustrate aspects of the design that form no part of the claim.
